UNITED STATES PATENT OFFICE.

ARTHUR W. DOWE, OF SAN FRANCISCO, CALIFORNIA.

PADLOCK.

1,326,394.

Specification of Letters Patent.

Patented Dec. 30, 1919.

Application filed January 27, 1919. Serial No. 273,501.

To all whom it may concern:

Be it known that I, ARTHUR W. DOWE, a citizen of the United States, residing at San Francisco, in the county of San Francisco, State of California, have invented new and useful Improvements in Padlocks, of which the following is a specification.

This invention relates to a lock of the padlock type; and the chief object of this invention is the provision of a simple form of padlock which is very difficult or impossible to pick.

There are several distinctive features pertaining to my new lock. The key hole of the lock is ordinarily covered by what I term the key hole cover; it is necessary to push the shackle back into the lock in order to open the key hole. Any person unacquainted with the operation of the lock would not know how to insert the key. After the key has been inserted to operate the tumblers, it must be withdrawn before the lock can be opened, before the shackle can be pulled out from the lock. This is another feature of operation which would ordinarily be unknown to those unfamiliar with the lock. When the shackle is pressed into the lock in order to insert the key, the stump is pressed away from the tumblers, so that there is nothing in contact with the tumblers which would serve as a guide or feeler by which the tumblers could be picked. If the stump is let back into contact with the tumblers, the key hole is automatically closed.

I explain my preferred form of construction in the following specification, the same being shown in the accompanying drawings, in which:

Figure 1 is a longitudinal section of my improved form of lock.

Fig. 2 is a cross section taken as indicated by line 2-2 of Fig. 1.

Fig. 3 is a cross section taken as indicated by line 3-3 of Fig. 1 showing the key in place.

Fig. 4 is a horizontal section taken as indicated by line 4-4 of Fig. 1.

Fig. 5 shows the various tumblers and tumbler spacing washers.

I may house my lock within any suitable casing, such as an ordinary padlock case 10. This casing may preferably be made in two halves and held together by suitable rivets 11. The shackle 12 is of ordinary construction projecting through openings 13 and 14 in the case and having on one side a shank

15 of reduced diameter around which the curved portion 16 of stump carrier 17 is adapted to fit. The stump carrier 17 rests against the front wall of the case and its curved portion fits into the reduced part of the shackle, so that the stump carrier moves vertically with the shackle. A suitable spring 18 presses the shackle and stump carrier upwardly. 65

Normally the stump 20 is pushed upwardly against the peripheries of the tumblers 21 into the position shown in Figs. 1 and 2. There is a small lug 22 on the lower end of the stump 20, which lug engages cam slot 23 in key hole cover 24. Key hole cover 24 has a key slot 25 which is normally out of register with key hole 26 in the case. 70 When the parts are in the position shown in Fig. 1 the key 27 cannot be inserted. By 75 moving the shackle 12 into the case, against the pressure of spring 18, the lug 22 will travel downwardly in the cam slot 23 and will cause the key hole cover to move to the right in Fig. 1 and cause the key slot 25 80 to register with the key hole 26. When the parts are in this position, the key 27 may be inserted and pressed upwardly against the tumbler lugs 29 to move the tumblers in the direction indicated by the arrow. 85 Each of the tumblers has a stump slot 30, and these slots 30 are arranged at different angles to the lugs 29. The key 27 has an end configuration which will press the lugs 29 to the correct position to throw all the 90 slots 30 into vertical positions directly above the stump 20. With the tumblers in position for unlocking, the stump carrier will not move upwardly until the key is removed, for the reason that the key prevents the 95 key hole cover from assuming its position shown in Fig. 1; and the stump 20 cannot move upwardly without the key hole cover moving laterally. As soon as the key is removed the spring 18 presses the stump 100 carrier and stump and shackle upwardly, causing the stump to enter the tumbler slots 30 and raising the free end of the shackle out of the case. To lock the mechanism, it is only necessary to press the shackle into 105 the case. An overhang 31 on the upper edge of the stump carrier 17 presses downwardly on the lugs 29 to press the tumblers into the positions shown in Fig. 1. The shackle and stump carrier may be pressed into the case 110 the distance required for such travel of the tumblers 31. When the shackle is pressed

into the case in order to insert the key, the member 31 is only pressed down a short distance, not far enough to interfere with the operation of the tumbler lugs 29 by the 5 key 27.

Each of the tumblers 21 is separated from its neighbor by a suitable stationary washer 32, each of the washers having a slot 33 therein for the passage of the stump 20. 10 The washers 32 have squared upper shoulders 34 which fit against the upper edge of the case to prevent rotation of the washers. In this manner the rotation of the one tumbler is prevented from causing rotation 15 of any of the others. The tumblers and washers are all mounted on a riveted stud 35 and are held sufficiently tightly to frictionally remain in any set position. However, I provide for the possibility of the 20 tumblers wearing loose by weighting each of the tumblers with a lug 36 so that the tumblers are gravitationally balanced. These lugs 36 also serve the purpose of steps to limit the tumblers' movements in the direction opposite to that indicated in Fig. 1, the lugs 36 engaging with one of the case rivets 11.

Having described a preferred form of my invention, I claim:

30 1. In a device of the character described, a lock case, a movable shackle therein, a stump movable with the shackle, tumblers cooperating with said stump, key hole in the case, and means cooperating with the 35 stump to cover said key hole when the stump is in engagement with the tumblers.

2. In a device of the character described, a lock case, a shackle movable therein, a stump carrier movably connected with the

shackle, a stump thereon, tumblers coöperating with said stump, and means coöperating with said stump carrier to prevent access of a key to said tumblers when the stump is in engagement with the tumblers. 40

3. In a device of the character described, a 45 lock case, a shackle movable therein, a stump carrier movable with the shackle, a stump thereon, tumblers coöperating with said stump, there being a key hole in the case opposite the tumblers, a key hole cover, and means coöperating with said cover and stump carrier whereby said cover obstructs the key opening when the stump is in engagement with the tumblers.

4. In a device of the character described, 55 a lock case, a shackle removable therein, spring means for pressing the shackle out of the case, a stump carrier movable with the shackle, a stump thereon, tumblers coöperating with said stump, the stump being 60 pressed into engagement with the tumblers by the spring operation of said shackle, there being a key hole in the case opposite the tumblers, a key hole cover, there being a cam slot in the key hole cover, a cam lug 65 carried on the stump engaging said cam slot, the operation of said lug and slot being to throw the key hole cover over the key hole when the stump engages the tumblers and to uncover the key hole when the stump 70 is pressed from the tumblers.

In witness that I claim the foregoing I have hereunto subscribed my name this 13th day of January, 1919.

ARTHUR W. DOWE.
